TREATMENT OF LEATHER BUTTS

Artur Metzger, Pinneberg (Holstein), Germany

Application June 4, 1954, Serial No. 434,487

Claims priority, application Germany June 6, 1953

13-Claims. (Cl. 69—46)

This invention concerns the treatment of leather butts by which is to be understood a piece of leather which has been tanned and beated is to be dressed, smoothed and strengthened.

The object of this invention is broadly the provision of an improved process and apparatus for treating leather butts.

Another object of the invention is to treat substantially the entire surface of a butt at one time.

A further object is to treat the entire butt at the same time so that the butt is straightened and flattened uniformly whereby it is of constant thickness and strength and is made completely smooth even if previously tanned in a drum tanner.

Yet a further object is the provision of an apparatus which will allow for local variations in thickness of the butt and which will produce a butt having a uniform surface.

The above and other objects and advantages of the invention will be more fully understood from the following description of the invention which is made with reference to the accompanying drawings. In the drawings:

Figure 1 is a side view, partly in section, of an apparatus for carrying out the process according to the invention;

Figure 2 is a section on the line II—II of Figure 1;

Figure 3 is a side elevation of a part of the apparatus in the direction of the arrow III of Figure 1,

Figure 4 is a section, to a larger size, of that part of the apparatus enclosed in the circle IV of Figure 1, and

Figure 5 is a plan view in the direction of the arrow V of Figure 4.

A table 2, which can be raised and held up under pressure by means of a hydraulic jack 3, constitutes the support plate for a butt 1. The pressing table and the hydraulic jack will not be described in greater detail since they may be of any conventional form. The hydraulic jack is supported on a base frame 4 which carries girders 8, by means of pillars 5, and longitudinal girders 6 and transverse girders 7, the girders 8 extending over the whole length of the table 2. Figure 1 shows that four parallel girders 8 are disposed adjacent one another. Suspended from the central pair of girders 8 through the agency of rollers 9 and links 10 is a plate 11 which is substantially co-extensive with the table 2. Plate 11 is completely smooth and of such thickness that it will not bend or deform when subjected to the pressure necessary for dressing and smoothing the butt. The rollers 9 run on suitable tracks in the central girders 8 so that the plate may be reciprocated lengthwise of the girders as later described.

Suspended from each of the two outer girders 8, through the agency of rollers 12 and links 13, is a longitudinal girder 14 and between the pair of girders 14 are rotatably mounted a plurality of pressure rollers 15, the axis of rotation of which is perpendicularly to the lengthwise direction of the girders 8. The rollers 12 run on suitable tracks in the outer supporting girders 8 so that the

2

rollers 15 can be reciprocated in the lengthwise direction of the supporting girders 8.

Carriages co-operating with an appropriate sliding surface on the supporting girders 8 could be used instead of the rollers 9, 12.

A longitudinal girder 17 is suspended from each of girders 14 by plates 16 and a relatively large number of rods or spindles 18 extend between the girders 17 parallel to the axis of rotation of the pressure rollers 15.

10 Each spindle 18 supports a roller assembly comprising a plurality of dressing or smoothing rollers 19 arranged close together and end to end. The distance between the spindles 18, which lie in a horizontal plane, is such that the diameters of the rollers in the individual rows substantially contact one another (Fig. 5). The rollers of adjacent rows are also staggered relatively to one another as shown in Figure 5.

The bore 20 of each roller 19 is substantially greater than the diameter of the spindle 18 so that each roller 19

20 fits loosely on its spindle 18 and therefore hangs loosely from the spindle, as shown in Figure 4. The supporting plate 11 is disposed immediately below the pressure rollers 15 and a rubber plate or mat 21 is between the lower surface of the supporting plate 11 and the rollers 19.

25 The rubber mat is substantially co-extensive with the surface of the plate 11 and therefore with the surface of the table 2.

There is also carried by the frame a shaft 22 which is driven, for example, by means of an electric motor (not shown) and a crank 23 on shaft 22 is connected with a shaft 25 by a rod 24 so that the supporting plate 11 is reciprocated, shaft 25 being rigidly connected to the plate 11 by arms 26 and 27. The connecting rod 24, crank 23, shaft 25 and arms 26 and 27 are arranged in the central longitudinal plane of the apparatus, a feature more particularly apparent from Figure 1. Girders 14 carry upstanding lugs 28 to each of which there is secured a bearing 29 for another connecting rod 30 which is actuated by crank 31 which is secured to the shaft 22.

30 The pressure rollers 15 and the dressing rollers 19 are reciprocated with the same stroke. However, this stroke is only half as great as the stroke of the supporting plate 11.

35 It will be apparent that the supporting plate 11, the pressure rollers 15 and the dressing rollers 19 hang freely from the supporting girders 8, and are longitudinally movable therealong. Disposed between the supporting plate 11 and the smoothing or dressing rollers 19 is the rubber mat 21, and it has been found that the latter, without additional securing means, remains in position for relatively 40 long periods of operation. The dressing rollers 19 are adjustable in so many ways that they can be satisfactorily adapted to the butt 1 to smooth, dress and strengthen the same.

45 I claim:

1. A process for treating butts comprising laying the butt on a flat, supporting surface, applying under pressure a plurality of parallel rollers to the butt and reciprocating the rollers across the butt, while applied thereto under pressure, so that substantially the entire butt is acted on by the rollers.

60 2. A process for treating butts comprising laying the butt on a flat, supporting surface, applying under pressure a plurality of close-pitched, parallel rollers to the butt, said rollers being substantially co-extensive with the butt and reciprocating the rollers across the butt, while applied thereto under pressure, so that substantially the entire butt is acted on by the rollers.

65 3. A process for treating butts comprising laying the butt on a flat, supporting surface, resiliently applying under pressure a plurality of close-pitched, parallel rollers to the butt, said rollers being substantially co-extensive

with the butts, and reciprocating the rollers across the butt, while applied thereto under pressure, so that substantially the entire butt is acted on by the rollers.

4. Apparatus for treating butts comprising a frame, a flat surface to support the butt, a plurality of parallel roller assemblies each comprising a plurality of rollers placed end to end, means to support said rollers from the frame for reciprocation, means for applying the rollers under pressure to the butt and means for reciprocating the rollers across the butt so that substantially the entire butt is acted on by the rollers.

5. Apparatus for treating butts comprising a frame, a flat surface to support the butt, a plurality of parallel roller assemblies each comprising a plurality of rollers placed end to end, the ends of the rollers of adjacent assemblies being staggered, means to support said rollers from the frame for reciprocation, means for applying the rollers under pressure to the butt and means for reciprocating the rollers across the butt so that substantially the entire butt is acted on by the rollers.

6. Apparatus for treating butts comprising a frame, a flat surface to support the butt, a plurality of parallel rollers to engage the supported butt, a plate-like member carried by the frame to support the rollers when applied to the butt, a rubber mat extending over the plate-like member between said member and the rollers, means to support said rollers from the frame for reciprocation, means for applying the rollers under pressure to the butt and means for reciprocating the rollers across the butt so that substantially the entire butt is acted on by the rollers.

7. Apparatus for treating butts comprising a frame, a flat surface to support the butt, a plurality of parallel rollers to engage the supported butt, a spindle for each roller, the rollers being loose on their spindles for considerable transverse movement relatively thereto, a plate-like member carried by the frame to support the rollers when applied to the butt, a rubber mat extending over the plate-like member between said member and the rollers, means to support the roller spindles from the frame for reciprocation, means for applying the rollers under pressure to the butt and means for reciprocating

said roller spindles to carry the rollers across the butt so that substantially the entire butt is acted on by the rollers.

8. Apparatus for treating butts comprising a frame, a flat surface to support the butt, a plurality of parallel rollers to engage the supported butt, a plate-like member carried by the frame to support the rollers when applied to the butt, a rubber mat extending over the plate-like member between said member and the rollers, means to support said rollers from the frame for reciprocation, means for applying the rollers under pressure to the butt, means for reciprocating the plate-like member across the butt so that substantially the entire butt is acted on by the rollers.

15 9. Apparatus according to claim 8 in which the stroke of the reciprocating plate-like supporting member is twice as great as the stroke of the reciprocating rollers.

10. Apparatus as claimed in claim 8 in which the plate-like supporting member bears against support rollers carried by the frame and extending parallel with the butt-engaging rollers.

11. Apparatus according to claim 10 in which the support rollers and the butt-engaging rollers are connected together for common reciprocation.

25 12. Apparatus as claimed in claim 11 wherein the stroke of the reciprocating plate-like supporting member is twice as great as the stroke of the commonly reciprocating butt-engaging and supporting rollers.

13. Apparatus for treating butts comprising a base frame, a hydraulic jack supported on said base frame, a table supported for movement by said jack and providing a flat support surface for a said butt, an overhead frame structure, a roller assembly comprising a plurality of side by side rollers, said roller assembly being carried 30 in suspended relation by said overhead frame structure, and means mounting said roller assembly for reciprocation across the butt while pressed against said roller assembly by said jack.
